FIG. 3.

Patented May 3, 1927.

1,627,282

UNITED STATES PATENT OFFICE.

ALBERT GRAN, OF CHICAGO, ILLINOIS.

RECEPTACLE.

Application filed November 11, 1925. Serial No. 68,422.

This invention relates to receptacles and more particularly to a waste basket.

Briefly stated, an important object of this invention is to provide a waste basket consisting of a number of separately formed sides and other parts which may be assembled without the exercise of unusual skill and which may be separately renewed should the same become dented, worn, or scratched.

10 A further and equally important object of the invention is to provide a waste basket in which the material used is already lithographed or otherwise decorated sheets so finished being cut and formed to suit requirements prior to the assembling of the basket and thereby obviating the labor and cost of applying a decorative finish to the basket after it has been assembled.

Another object of the invention is to provide a metallic receptacle of the character specified which is of highly simplified construction, durable in use, and cheap to manufacture.

Other objects and advantages will be apparent during the course of the following description.

In the accompanying drawings forming a part of this application and in which like numerals are employed to designate like parts throughout the same,

Figure 1 is a perspective of the improved waste basket;

Fig. 2 is a horizontal sectional view taken on line 2—2 of Fig. 1;

35 Fig. 3 is a vertical transverse sectional view taken on line 3—3 of Fig. 1;

Fig. 4 is a fragmentary plan view illustrating one of the corners of the waste basket, partly in section;

40 Fig. 5 is a group perspective illustrating one of the corner members or caps;

Fig. 6 is a fragmentary group perspective illustrating the corner flanges of the sides of the metallic receptacle;

45 Fig. 7 is a transverse sectional view taken on line 7—7 of Fig. 4;

Fig. 8 is a sectional view taken on line 8—8 of Fig. 4;

50 Fig. 9 is a detail sectional view taken on line 9—9 of Fig. 3, indicating a preliminary operation;

Fig. 10 is a horizontal sectional view taken on line 10—10 of Fig. 3; and

55 Fig. 11 is a fragmentary perspective of one of the corner posts or pedestals and the attaching means therefor.

In the drawings, wherein for the purpose of illustration is shown a preferred embodiment of the invention, the numerals 5 designate a plurality of more or less similarly formed metallic sides which have already been cut and formed from lithographed or decorated sheets furnished by a shop or plant equipped for work of that class. Obviously, the cutting and forming of parts already decorated eliminate the need of finishing or decorating the basket after it has been put together.

Figures 2 and 6 illustrate that the edge portions of the sides 5 are provided with L-shaped flanges 6 adapted to be arranged in opposed relation so that the same may be received in metallic corner strips 7 of channel shaped formation. The corner strips 7 which are split for their full length are applied from the lower ends of the flanges 6 and will draw the flanges together in the manner shown in Fig. 2. More specifically, the longitudinally split corner strips 7 may be somewhat flattened so that the inner portions of the flanges 6 are drawn tightly together. This exerts a clamping action upon the meeting portions of the sides so that the corner of the basket is firm and rigid; also, by the use of this connection dirt is prevented from working its way into the space between the L-shaped flanges.

The flanges 6 and the tubular corner strips 7 are extended a suitable distance below the major portions of the sides to receive the shanks of pedestals or feet 10 and U-shaped spring fasteners 11. Each spring fastener 11 is arranged about the shank of the pedestal 10 so as to hold the shank in place within the corners of the basket. The pedestals 10 may have rounded floor contact surfaces.

Fig. 1 clearly illustrates that strengthening and reinforcing split metallic sleeves 14 are positioned on the lower portions of the corner strips 7 so as to hold the lower portions of the corner strips firmly in engagement with the flanges 6 and at the same time assist in holding the corner pedestals 10 in place. The split sleeves 14 also add to the attractiveness of the basket.

Fig. 3 illustrates that the bottom 16 of the basket is provided with marginal return flanges 18 which are interlocked with inwardly-directed return flanges 20 formed from the lower ends of the sides 5.

Referring now to Figs. 3 and 6, it will be seen that the upper portions of the sides are

provided with outwardly directed L-shaped flanges 26 which are received in and are concealed by tubular cap rails 27. The rails 27 are split so that the same will slide on the flanges. This feature of the invention is clearly illustrated in Fig. 6 wherein it shows that the split cap rails 27 which are of more or less rectangular formation fit on the flanges 26 and provide a smooth and artistic top for the basket. One longitudinal edge portion of each cap rail 27 is extended inwardly to form a flange 28 which frictionally bears on the upper surface of the flange 26 so as to cooperate with the under side of the cap rail in securely holding the cap rail in place. Attention is especially directed to the fact that even though the cap rails 27 are split longitudinally, no sharp edges are visible or are likely to come into contact with the hands of a person handling the basket. Furthermore, dust or trash is not likely to lodge between the cap rail and any other parts of the basket.

Each corner cap consists of two separate angle or L-shaped bars 30 and 31 adapted to be positioned over the corner strips 7 and received in the terminal portions of the cap rails 27 in the manner shown in Fig. 4. When the angle bars 30 and 31 are extended into the ends of the cap rails 27 they are firmly held in place and a portion of the flange 28 of each cap rail 27 may be bent up into each of the notches 33 in the under sides of the bars 30 so as to prevent accidental displacement of the corner caps. A cushioning element 36 of rubber or other suitable material may be held at the outer edge of each angle bar 31 by means of retaining plates 37 and 38, the plates 37 and 38 being held in place by screw bolts 40 or the like. As is noted the latter pass through a clearance space between the corners of the angle bars 30 and 31. These bars are made in two pieces to provide this space without drilling and also to facilitate bending from cold material, since this operation with a bar of double width would cause it to break. It will be seen that when the flanges at the edges of the plates 37 and 38 are forced into gripping engagement with the cushion 36, the cushion will be firmly held in place and will prevent the basket from marring a desk or other object with which it may accidentally come in contact. By the same token the cushioning elements at the corners of the basket will protect the basket.

With reference to the foregoing description taken in connection with the accompanying drawings it will be seen that the peculiar formation of the novel basket from ready-cut and finished units not only speeds up assembly and production of the article, but does away with the necessity of decorating and finishing each basket after as-

sembled. Thus, the manufacture of the basket requires no decorating equipment such as paint vats, materials, tanks, etc., and no artisans in that connection. As previously mentioned, the sheet-stock is secured from another source, decorated to suit and ready to cut and form.

The novel construction eliminates sharp edges and dust passages, greatly increasing the desirability of the basket. Also, the fact that the parts of the basket are interchangeable provides a construction which is highly desirable, as any part which has become marred or dented during or after assembling may be easily replaced at low cost.

In assembling the basket from a given set of parts, it is first seen that these are assembled in unitary groups to reduce the labor of the major assembly. Thus, the angle bars 30 and 31, cushioning element 36, retaining plates 37 and 38 and screw 40 are grouped into an integral unit, as indicated in Fig. 4. Next, the split sleeves 14 are slid upon the corner strips 7. The rails 27 are now applied to the flanges 26 of the respective sides 5, these of course being separately laid out as yet. Now, taking two of the sides 5, one section of each angle bar assembly is fitted into the open ends formed by the flanges 26 and rails 27, as suggested in Fig. 4. The two assemblies so formed are now stood up opposite each other in the position suggested by the design of the basket, and the adjacent assemblies of the remaining sides 5 set up to complete the wall enclosure. By gathering the two first-described side assemblies, the projecting sections of the angle bars 30 and 31 will become fitted into the cap rails of the adjoining sides. The angle irons are now locked in the cap-rail assembly by a suitable tool which forces a portion of the flange 28 of each cap rail into a notch 33 in the underside of each bar 33, as previously described. With the top of the basket connected, the structure is inverted and the corner strips 7 slid-free ends first—up the corner flanges 6 of the sides 5 until the underside of the angle irons 30 and 31 is reached. The structure is now righted and the bottom 16 dropped in. Before this is done, however, it must be seen that the interlocking flanges 18 and 20 are open, as indicated in Fig. 9, to permit the bottom to drop into place without impediment. A press of suitable design is now applied to interlock the flanges 18 and 20 and thus make the bottoms rigid and secure. The pedestals 10, spring-capped 11, are now driven up the tubular footing for the structure.

It is noted that the cap-rails 27 have their ends terminate short of the corners of the basket. It is also noted that the angle bars 30 and 31 serve to prevent longitudinal

movement of the rails 27, this result being attained by the engagement of the struckup portions of the flange 28 of rail 27 in the notches 33 of the angle bar 30. It is also observed that the corner plates 37 carrying the cushioning element 36 conceal the angle bars 30 and 31,—that is the intermediate part not enclosed by rails 27,—and forms a very attractive and effective corner construction.

Having thus described the invention, what is claimed is:

1. In a receptacle of the class described, the combination with the side walls, of bead sections slidable along the top edges and constituting the rim of the receptacle, corner pieces having angularly protruding arms, said bead sections having sockets for receiving said arms, and each of said arms having notches therein, and each of said sockets having partially severed portions adapted to be struck into said notches whereby to hold said corner pieces and bead sections assembled.

2. In a receptacle of the class described, the combination with the side walls, of bead sections slidable along the top edges and constituting the rim of the receptacle, corner pieces having angularly protruding arms, said bead sections having sockets for receiving said arms, and means associated with said sockets and arms whereby the bead sections and corner pieces will be rigidly united and the bead sections will be prevented from partaking of a sliding movement to disengage themselves from the receptacle.

3. In a receptacle of the class described, means for connecting adjacent sides comprising an angle bar, said sides having socket portions receiving the arms of said angle bar, and means associated with each angle bar arm and its socket for positively holding the same in fixed relation.

4. In a receptacle of the class described, means for connecting adjacent sides comprising an angle bar, said sides having socket portions receiving the arms of said angle bar, means associated with each angle bar arm and its socket for positively holding the same in fixed relation, cushioning elements carried by said angle bars, and opposed clamping plates for holding said cushioning elements in place said clamping plates concealing the exposed portions, of the arms of said angle bars.

5. A receptacle of the character specified comprising a plurality of sides, tubular corner strips connecting the sides, the upper portions of said sides being provided with laterally projecting flanges, cap rails of

tubular formation receiving said flanges, and corner members having angle bars extended into said cap rails and held in place thereby, said angle bars being extended over said corner strips to close the same.

6. A receptacle of the character specified comprising a plurality of sides, tubular corner strips connecting the sides, the upper portions of said sides being provided with laterally projecting flanges, cap rails of tubular formation receiving said flanges, corner members having angle bars extended into said cap rails and held in place thereby, said angle bars being extended over said corner strips to close the same, and cushioning elements carried by said corner members and projecting beyond the sides of the receptacle to protect the same.

7. A metallic receptacle comprising sides, corner strips connecting the sides, angle bars arranged over the corner strips, cushioning elements associated with said angle bars, and plates engaging the cushioning elements and holding the same in place, said plates being positioned at opposite sides of said angle bars.

8. A metallic receptacle comprising sides, corner strips connecting the sides, angle bars arranged over the corner strips, cushioning elements associated with said angle bars, plates engaging the cushioning elements and holding the same in place, said plates being positioned at opposite sides of said angle bars, and cap rails secured to the upper portions of said sides and receiving said angle bars to hold the same in place.

9. A metallic receptacle comprising a plurality of sides having their upper portions provided with laterally directed L-shaped flanges, longitudinally split cap rails receiving said flanges and being provided with inwardly extending edge portions engaging the upper sides of said flanges, and corner members extending into said cap rails and held in place thereby.

10. A metallic receptacle comprising a plurality of sides having their upper portions provided with laterally directed L-shaped flanges, longitudinally split cap rails receiving said flanges and being provided with inwardly extending edge portions engaging the upper sides of said flanges, corner members extending into said cap rails and held in place thereby, and cushioning means carried by said corner members and projecting beyond the sides of said receptacle.

In testimony whereof I affix my signature.

ALBERT GRAN.
